UNITED STATES PATENT OFFICE.

GEORGE RIEXINGER, OF BUFFALO, NEW YORK.

MECHANICAL TOY.

1,015,343.

Specification of Letters Patent.

Patented Jan. 23, 1912.

Application filed May 12, 1911. Serial No. 626,754.

To all whom it may concern:

Be it known that I, GEORGE RIEXINGER, a citizen of the United States, residing at Buffalo, in the county of Erie and State of New York, have invented new and useful Improvements in Mechanical Toys, of which the following is a specification.

This invention relates to mechanical toys.

Its object is the production of an interesting and attractive toy of this kind representing a boxing contest.

In the accompanying drawings: Figure 1 is a side elevation of the toy with a portion of its base broken away. Fig. 2 is a top plan view thereof, partly in section. Fig. 3 is a fragmentary rear view of the toy. Fig. 4 is a fragmentary vertical section of line 4—4, Fig. 2.

Similar letters of reference indicate corresponding parts throughout the several views.

A indicates the stationary base or main frame of the toy which is hollow and preferably rectangular, although it may be circular or of any other suitable form. Rising from the corners of the base are posts B to which a cord b is attached extending around the four sides of the device to represent the inclosure of the boxing ring or arena.

Within the upper portion of the hollow base is arranged a movable platform or floor C adapted to rock or vibrate for the purpose of actuating certain movable parts 35 of figures D representing the boxers. In the preferred construction shown in the drawings, the platform is pivoted at its front and rear corners to the base, as shown at e. A rocking motion is imparted to this 40 platform by any suitable means. The preferred mechanism shown in the drawings comprises a horizontal crank shaft F supported in brackets f f² secured to the base A and extending through the adjacent wall 45 of the latter. The wrist pin f¹ of this crank shaft is connected by a link g with a lug g¹ secured to the upper side of the platform. To the outer end of this crank shaft is secured a gear pinion h which meshes with 50 a driving gear H having a hand crank h¹ and mounted on a stud i carried by a bracket I arranged above the bracket f.

The boxing figures D are arranged in a facing attitude immediately above the platform C and their body-portions d are preferably rigidly mounted on a cross bar or sup-

port J secured at its ends to diagonally opposite posts B. One arm d¹ of each figure may be made in one piece and pivoted to the body, as shown at k, so as to swing vertically. The inner member d² of the other arm is rigidly secured to the body, while the fore-arm d³ thereof is pivoted to said inner member by a horizontal pin l, so that said fore-arm is free to swing toward and from the opposing figure.

One leg of each figure is placed forward of the other and may be formed integral with or rigidly secured to the body portion thereof. The lower section d⁴ of the other leg is pivoted at its lower end to a lug of the platform C by a horizontal pin m, while its upper end is pivoted by a similar pin n to the rigid thigh-portion of the last-named leg. The pin n passes through a vertical slot o in said lower leg-section to permit the latter to rise and fall on the rigid portion of the body in following the rocking movements of the platform.

A link p connects the vertically-movable leg section of each figure with the arm d¹ on the same side of the body, so as to cause said arm to vibrate vertically in unison with the platform, producing a stroke or blow in imitation of the so-called "upper cut". The movable member of the other arm of each figure is connected by a link q with the upper arm r of a bell crank lever pivoted at r¹ to the body of the corresponding figure. The lower arm r² of this lever is connected by a link s with the lower leg-section d⁴. It will be observed that by these connections the rocking movement of the platform produces a forward and backward movement of the movable fore-arms 95 of the figures in imitation of the sparring movements of boxers.

In order to add to the attractiveness of the toy, the heads as well as the arms are made movable. For this purpose they are 100 pivoted at t to the body portions and their upper portions are connected by horizontal pivots t¹ with the upper ends of the bell-crank levers r.

It will be understood from the foregoing 105 that both figures are identical in construction, but as they face each other, the jointed left arm of one figure is drawn back when that of the other is moved forward and the heads of the figures vibrate in unison with 110 said jointed arms, while the right arm of one figure is swung down when that of the

other figure is swung up, thus imitating in an interesting manner the blows and gestures of boxers.

It will be noted that by simply turning 5 the driving wheel H, both figures are actuated through the medium of the rocking platform C and intermediate connections. As the movable parts of both figures are connected with opposite ends of the same actuator, *i. e.* the platform C, the toy is correspondingly simplified in construction and its 10 cost of production reduced accordingly.

While the invention is herein shown as applied to figures representing boxers, I do 15 not wish to limit the same to that particular use, as it is obviously applicable within the scope of the claims to figures of similar toys.

I claim as my invention:

1. In a toy, the combination of a base, a 20 vibratory platform pivoted centrally to the base, a pair of figures supported above the platform and each having a movable part, and actuating connections between the movable parts of the figures and the platform, 25 the connections of the two figures being attached to the platform on opposite sides of its pivot.

2. In a toy, the combination of a base, a vibratory platform mounted thereon, a figure 30 supported above the platform and having an upper movable part and a lower leg-section movable vertically on the body portion of the figure, the lower end of said leg-section being pivoted to the platform to 35 vibrate vertically therewith, and means for operatively connecting said upper movable part of the figure with said movable leg-section.

3. In a toy, the combination of a base, a 40 vibratory platform mounted thereon, a figure supported above said platform and having an arm provided with a jointed fore-arm, a lever pivoted to the body of the figure and connected with said jointed fore-arm, 45 and means for operatively connecting said lever with the platform.

4. In a toy, the combination of a base, a vibratory platform mounted thereon, a figure supported above said platform and provided with arms, one of said arms having a 50 jointed fore-arm and the other arm being pivoted to the body of the figure, a lever pivoted to the body of the figure and connected with said fore-arm, means for oper- 55 atively connecting said lever with the platform, and means for operatively connecting

the other arm of the figure with the platform.

5. In a toy, the combination of a base, a vibratory platform mounted thereon, a figure 60 supported above the platform and having an arm provided with a jointed fore-arm and a leg-section movable vertically relatively to the body of the figure, said leg-section being pivoted to the platform to 65 vibrate therewith, a bell crank lever pivoted to the body of the figure, a link connecting the upper arm of said lever with said fore-arm, and a second link connecting the lower arm of said lever with said movable leg-section.

6. In a toy, the combination of a base, a vibratory platform mounted thereon, a figure supported above the platform and having a movable head and a movable arm, a 75 lever pivoted to the body of the figure and operatively connected with said platform, and means for operatively connecting the head and said arm with said lever.

7. In a toy, the combination of a base, a 80 vibratory platform arranged thereon, a stationary support carried by the base, said support being arranged above the platform and extending across the same, a figure comprising a body-portion secured to said support and a part movably attached to said body-portion, and means for operatively connecting said movable part with said platform.

8. In a toy, the combination of a base, 90 posts rising from opposite sides thereof, a cross bar mounted on said posts, a vibratory platform supported on the base below said cross bar, a figure mounted on said cross bar and having a movable part, and means 95 for operatively connecting said movable part with the platform.

9. In a toy, the combination of a base, a vibratory platform mounted on the base, a figure supported above the platform and 100 having a movable part, means for operatively connecting said movable part with the platform, a horizontal crank shaft supported on the base below the platform, and an operative connection between said crank shaft 105 and the platform.

Witness my hand this 10th day of May, 1911.

GEORGE RIEXINGER.
